UNITED STATES PATENT OFFICE.

LEE S. CHADWICK, OF EAST CLEVELAND, OHIO, ASSIGNOR TO THE CLEVELAND METAL PRODUCTS COMPANY, OF CLEVELAND, OHIO, A CORPORATION OF OHIO.

MEANS FOR CONNECTING HYDROCARBON-BURNERS TO SUPPLY-PIPES.

1,336,423.

Specification of Letters Patent.

Patented Apr. 13, 1920.

Application filed April 26, 1916. Serial No. 93,583.

To all whom it may concern:

Be it known that I, LEE S. CHADWICK, a citizen of the United States, residing at East Cleveland, in the county of Cuyahoga and State of Ohio, have invented a certain new and useful Improvement in Means for Connecting Hydrocarbon-Burners to Supply-Pipes, of which the following is a full, clear, and exact description, reference being 10 had to the accompanying drawings.

This invention relates to improvements in hydrocarbon burners of the sort that are communicatively connected to and are supported solely by a fuel supply pipe, an example of such a burner being found in the 15 patent to Jeavons, No. 1,039,950, issued October 1, 1912. More particularly, the invention relates to improved means for communicatively connecting the burner to the 20 supply pipe and for securing or clamping the burner and pipe together so that the former is held against turning with respect to the latter.

The objects of the invention are to provide 25 a leak proof connection between the burner and pipe that is extremely simple, and consequently cheap of production; to provide a connection of the aforesaid nature that will effectually lock the burner against turning with respect to the pipe; to provide a construction wherein the original 30 thickness of the pipe is maintained at the zone of its communicative connection with the burner (which is not the case in prevailing constructions of this 35 sort); to associate with the supply connection certain clamping elements which contact with the connection to firmly clamp the burner to the pipe, and wherein a constant 40 tension exists when the parts are completely assembled, thus assuring a permanent clamping action; to provide means for accomplishing the immediately foregoing object in a very simple and economical manner; and to 45 produce a construction through which the above objects are attained, and which may be very conveniently and quickly assembled and disassembled.

In the accompanying drawings—

Figure 1 is a central vertical section 50 through the lower portion of a hydrocarbon burner connected to a supply pipe in accordance with my invention; Fig. 2 is a perspective view of the elbow and packing washer shown in Fig. 1; Fig. 3 is a frag-

mentary perspective view of the pipe, showing the seat for the washer and elbow of the preceding figure; Figs. 4, 5, and 6 correspond, respectively, to Figs. 1, 2, and 3, and show a slightly modified form of elbow 60 and pipe seat; Fig. 7 is a central vertical section through a connection similar to that of Fig. 4, and wherewith certain clamping elements are associated; Fig. 8 is a perspective view of the clamping elements of Fig. 7; 65 Fig. 9 is a perspective view of the clamp used in the forms of my invention illustrated in Figs. 1 and 4; and Fig. 10 is a perspective view of a locating fork for the side of the burner opposite the supply fitting. 70

The style of burner with which my invention is used is well known to those familiar with the art, the same comprising an inner and an outer wick tube that are 75 spaced apart in concentric relation and connected together and sealed against leakage at their lower ends to produce an annular chamber for the reception of a wick, the burner being referred to, generally, in the 80 drawings, by the reference letter A, and the supply pipe to which it is connected, by the reference letter B.

It will be found upon referring to the Jeavons's patent, mentioned toward the beginning 85 of this specification, that the joint between the supply connection or elbow of the burner, and the supply pipe, is of quite a complicated nature. Prior to my present invention, to the best of my knowledge, connections were made between the supply connection of the burner and the supply pipe 90 according to the method shown in this patent, to wit, by cutting a flat seat upon the supply pipe surrounding the hole through 95 which the burner communicated with the pipe, and placing some sort of packing member between the pipe and the supply connection. This resulted in reducing the thickness of the pipe materially in the vicinity 100 of the hole, thus weakening the pipe. Also, because of the contour of the pipe, the seat was of very slight lateral extent, and consequently had very little effect in holding the burner against turning with respect to 105 the pipe.

It is my intention to overcome this difficulty by pressing a seat in the pipe, as illustrated (in one form) in Figs. 1 and 3. By thus pressing the seat in the pipe, the seat 110

may be made of considerable lateral extent, and the hole b^1 for receiving the cylindrical extension 3^a of the elbow 1^a , is central of the seat.

- 5 A compressible washer 50, preferably of lead, or a satisfactory substitute therefor, is interposed between the seat that is formed in the pipe and the shoulder 51 of the elbow, which surrounds the extension 3^a . The angular face of the shoulder 51 is preferably, at right angles to the axis of the extension 3^a , and parallel to the straight seat of the pipe, and in the angle between the shoulder and the extension, there is formed a groove 52 into which a quantity of the washer 50 is forced, when the parts are bound together by the clamp C' , presently to be described. The outer wall of the groove 52 is inclined upwardly and inwardly toward the extension 3^a so as to exert an inward force upon the portion of the washer which occupies the groove, thus causing the washer to firmly hug the extension and more effectually seal the joint against leakage.
- 25 The clamp C' is constructed of a strap or band which is split beneath the pipe, and the screw 56 passes through an aperture in the central portion of the strap, the ends of the strap being soldered, or otherwise secured to the underneath side of the pipe, thus effectually holding the burner against angular movement with respect to the pipe. The burner is held against swinging laterally in a horizontal plane by the locating fork 44.

- In Figs. 4 and 6 I have shown a tapered seat in the pipe B that is obviously simpler to produce by a pressing operation than the straight seat illustrated in Figs. 1 and 3.
- 40 For use in connection with this tapered seat I employ the elbow shown in perspective in Fig. 5, and in central section in Fig. 4, the only difference between this and the elbow shown in Figs. 1 and 2 being in the angular relation of the shoulder 57, with respect to the axis of the extension 3^b , such angle conforming to the angular inclination or taper of the seat formed to the pipe.

- The clamp C' is employed in connection with this form of my invention, as in the case preceding.

- In the form of my invention illustrated in Figs. 7 and 8, I employ a plate 60 that is attached to the burner adjacent the supply connection and extends outward along the upper side of the supply pipe, the plate having an opening through which the supply connection may extend and enter the aperture of the pipe. The plate terminates, at its outer end, in bearing portions 61 that are forced, by the clamp C , into contact with the upwardly facing abutment portions 62 of a saddle 63 that embraces the upper side of the supply pipe and is soldered or otherwise secured thereto. Thus, the abutment

portions of the saddle are, in effect, lateral projections of the supply pipe, and the co-operating portions of the plate 60 exert a downward thrust thereon when the clamp C is rendered effective. This construction very securely holds the burner against turning with respect to the pipe.

The locating fork 44, hereinbefore generally referred to, may have one or both of its branches provided with a set screw 65. In such a case, the end of the branch is twisted through about 90° from the plane of the body portion of the fork, and tapped for the reception of the screw 65. Preferably, the screw reposes slightly below the horizontal center of the pipe, so that it will create somewhat of a wedging action when screwed in against the pipe, functioning to draw the burner firmly down against the pipe, at the same time making the withdrawal of the fork from the pipe practically impossible.

When opposed set screws are employed, the burner may be adjusted transversely of the pipe in either direction by loosening one screw and setting up on the other, the fork being made sufficiently wide, in this event, to allow for such adjustment.

To afford sufficient thread bearing for the screw 56 associated with clamp C' , I employ a nut 56^a which is shown as a square nut of standard type, and the nut is confined between the side branches of the strap or band 55 against turning when the screw is screwed down against the fitting 1^a .

Having thus described my invention, what I claim is:

1. The combination of a supply pipe having an aperture, a burner having a supply connection that is provided with an extension that is adapted to be received by said aperture, and a clamp permanently secured to the pipe, said clamp acting to bind the supply connection and the supply pipe together.

2. The combination of a supply pipe having an aperture and a depressed seat surrounding said aperture, a burner having a supply connection that is provided with an extension adapted to be received by said aperture, and having also a shoulder for co-operation with the aforesaid seat, the shoulder and seat being correspondingly tapered inward toward the aperture, a washer of compressible material interposed between the shoulder and seat, and means for clamping the pipe and the supply connection together.

3. The combination of a supply pipe having an aperture and a depressed portion surrounding said aperture, a burner having a supply connection that is provided with an extension adapted to be received by said aperture, and having also a portion surrounding the same for co-operation with the

aforesaid portion of the pipe, one of said coöperating portions having an annular groove surrounding the extension, the outer wall whereof is inclined with respect and opposed to the surface of said extension, a washer of compressible material interposed between said portions, and means for clamping the pipe and the supply connection together.

10 4. The combination of a supply pipe having an aperture and a depressed seat surrounding the aperture, a burner having a supply connection that is provided with an extension adapted to be received by the aperture, and having also a shoulder surrounding said extension for coöperation with the aforesaid seat, the shoulder and seat being correspondingly tapered inward toward the extension and aperture, the connection having an annular groove within the angle between its extension and shoulder, the outer wall of said groove converging inward from the shoulder, a washer of compressible material between the shoulder and seat, and a 25 clamp for binding the supply connection and pipe together.

5. The combination of a supply pipe having an aperture, a burner having a supply connection that is provided with an extension adapted to be received by said aperture, a band that extends over the supply connection and is secured to the pipe, a screw extending through the band and bearing upon a portion of the supply connection opposed to the aforesaid extension, and a nut between the band and connection through which the screw is threaded, said nut being confined against turning and against movement away from the supply connection by 35 the surrounding portion of said band.

6. The combination of a supply pipe having an aperture, a burner, a clamping plate extending laterally from one side of the burner and along the pipe, a member embracing the pipe, said member and the clamping plate having coöperating portions whereby they are held together, the burner having a supply connection, said supply connection having an extension that is adapted 45 to be received by the aperture, and means for binding the supply connection and pipe together.

7. The combination of a supply pipe having an aperture, a burner, a clamping plate extending laterally from one side of the burner and along the pipe, said pipe having lateral extensions and the clamping plate having portions which coöperate therewith whereby they are held together, the burner having a supply connection that is provided with an extension adapted to project into the aperture of the pipe, and means for binding the supply connection and pipe together.

65 8. The combination of a supply pipe hav-

ing an aperture, a burner, a clamping plate extending laterally from the burner and along the apertured side of the pipe, the clamping plate having an opening through which the aperture is exposed, a tension member embracing the opposite side of the pipe, said tension member and the clamping plate having coöperating portions whereby they are held together, the burner having a supply connection that is provided with an extension adapted to project through the opening of the clamping plate and into the aperture of the pipe, and means for binding the supply connection and pipe together, the clamping plate and tension member being so proportioned as to be placed under tension when the extension occupies its normal position within the aperture.

9. The combination of a supply pipe having an aperture, a burner, a clamping plate extending laterally from the burner and along the apertured side of the pipe, the clamping plate having an opening through which the aperture is exposed, a tension member embracing the underneath side of the pipe, said tension member and the clamping plate having coöperating portions whereby they are held together, the burner having a supply connection that is provided with an extension adapted to project through the opening of the clamping plate and into the aperture of the pipe, means for binding the supply connection and pipe together, the clamping plate and tension member being so proportioned as to be placed under tension when the extension occupies its normal position within the aperture, and a locating device attached to the side of the burner opposite the clamping plate for co-operation with the pipe.

10. The combination of a supply pipe having an aperture, a burner, a plate extending laterally from the burner and along the apertured side of the pipe, the plate having an opening through which the aperture is exposed and terminating at its outer end in opposed bearing extensions, a saddle embracing the upper side of the pipe and having notches with the bottom walls of which the bearing extensions of the plate engage, the burner having a supply connection that is provided with an extension adapted to project through the opening of the plate and into the aperture of the pipe, and means for binding the supply connection and pipe together.

11. The combination of a supply pipe having an aperture, a burner, a plate extending laterally from the burner and along the apertured side of the pipe, the plate having an opening through which the aperture is exposed, a saddle embracing the upper side of the pipe and having upwardly facing bearing surfaces wherewith portions of the aforesaid plate engage, the burner having a

- 5 supply connection that is provided with an extension adapted to project through the opening of the plate and into the aperture of the pipe, and means for binding the supply connection and pipe together.
  - 10 12. The combination of a supply pipe having an aperture, a burner, a plate extending laterally from the burner and along the apertured side of the pipe, the plate having an opening through which the aperture is exposed, opposed lateral extensions carried by the pipe, the upper sides of which are engaged by portions of the plate, the burner having a supply connection that is provided with an extension adapted to project through the opening of the plate and into the aperture of the pipe, and means for binding the supply connection and pipe together.
  - 15

13. The combination of a supply pipe having an aperture and a seat surrounding the aperture, a burner having a supply connection that is provided with an extension adapted to be received by said aperture, said connection having a surface opposed to the aforesaid seat, a washer of compressible material interposed between the surface and seat, and means for binding the pipe and supply connection together.

In testimony whereof, I hereunto affix my signature in the presence of two witnesses.

LEE S. CHADWICK.
